(57) **CLAIM**

The ornamental design for a gasoline container with bottom recessed handle, as shown and described.

DESCRIPTION

FIG. 1 is an isometric view of a gasoline container with bottom recessed handle showing my new design;

FIG. 2 is a right side elevation view thereof, the opposite side being a mirror image of the shown;

FIG. 3 is a front elevation thereof;

FIG. 4 is a rear elevation view thereof;

FIG. 5 is a top plan view thereof; and,

FIG. 6 is bottom plan view thereof.
